DESIGN FOR A PORTABLE FIRE EXTINGUISHER

Jay Lawrence Seat, Fairfield, Conn.

Application September 18, 1936, Serial No. 64,915

Term of patent 3½ years

To all whom it may concern:

Be it known that I, Jay Lawrence Seat, a citizen of the United States, residing at Fairfield, in the county of Fairfield and State of Connecticut, have invented a new, original, and ornamental Design for a Portable Fire Extinguisher, of which the following is a specification, reference being had to the accompanying drawing forming part thereof.

Figure 1 is a side elevational view of a portable fire extinguisher, showing my new design.

Figure 2 is a reverse side elevational view thereof.

Figure 3 is a top plan view.

Figure 4 is a front elevational view of the same.

I claim:

The ornamental design for a portable fire extinguisher, as shown.

JAY LAWRENCE SEAT.
